UNITED STATES PATENT OFFICE.

RICHARD D. YOUNG, OF BROOKLYN, NEW YORK.

DESIGN FOR BOTTLE-STOPPERS.

Specification forming part of Design No. **7,409**, dated April 28, 1874; application filed April 11, 1874.
[Term of Patent 14 years.]

To all whom it may concern:

Be it known that I, RICHARD D. YOUNG, of Brooklyn, in the county of Kings and State of New York, have invented a new and original Design for a Bottle-Stopper, of which the following is a specification:

The accompanying drawings represent my design for a bottle-stopper in side elevation in Figure 1, and in section in Fig. 2.

The design consists of the trefoil-shaped top A.

I claim as my invention—

The design for a bottle-stopper, consisting of the trefoil-shaped top A, substantially as shown in the drawing.
